UNITED STATES PATENT OFFICE

SAHATIEL G. MANDALIAN, OF NORTH ATTLEBORO, MASSACHUSETTS

DESIGN FOR A METALLIC MESH FABRIC

Application filed November 21, 1931. Serial No. 41,798. Term of patent 7 years.

To all whom it may concern:

Be it known that I, SAHATIEL G. MANDALIAN, a citizen of the United States, residing at North Attleboro, in the county of Bristol and State of Massachusetts, have invented a new, original, and ornamental Design for a Metallic Mesh Fabric, of which the following is a specification.

In the accompanying drawings which form a part of this specification Figure 1 is a front

view of a portion of metallic mesh fabric showing my new design.

Fig. 2 is a fragmentary rear perspective view of the metallic mesh fabric to a somewhat enlarged scale.

I claim:—

The ornamental design for a metallic mesh fabric, as shown.

SAHATIEL G. MANDALIAN.
